UNITED STATES PATENT OFFICE.

AUGUST BREHMER, OF LEIPSIC, GERMANY.

PAPER-BOX MACHINE.

SPECIFICATION forming part of Letters Patent No. 366,146, dated July 5, 1897.

Application filed May 17, 1886. Serial No. 202,353. (No model.)

To all whom it may concern:

Be it known that I, AUGUST BREHMER, of Leipsic, Germany, have invented a new and Improved Paper-Box Machine, of which the following specification is a full, clear, and exact description.

This invention relates to a machine for making and cutting off clasps from wire and uniting the corners of pasteboard paper boxes with such clasps.

The invention consists in the various elements of improvement hereinafter more fully described.

In the accompanying drawings, Figure I represents a side view of the machine. Fig. II is an end view of the same. The other thirteen figures represent several parts in detail, and show the same in various positions of the operation.

Similar letters represent similar parts in all the figures.

A is the frame of the machine, the top surface of the projecting forward end, D, forming an angle of ninety degrees to receive two sides of the box to be united. On a bolt, E, fast in the frame the lever 1 turns, operated either by hand, foot, or power.

B is a lever turning on pin 3, attached to the frame A. On the forward head, C, of this lever all parts are supported and guided necessary for forming, bending, and driving the clasps around the corners and into the sides of the boxes. The various parts receive their motion from segments 4 and 5, turning on bolts 6, on the sides of the head C of lever B, and connected through rod 2 with the upper end of the lever 1. These segments 4 and 5 are connected together at their upper ends by bolts 8, and are provided with cam-shaped grooves to operate the various parts, as hereinafter more fully described. The lower end of the lever B is provided with a roller, 39, working in a cam-shaped groove, 40, made in the lever 1, to communicate motion to said

lever B. The pasteboard pieces to form the box are placed upon the angular top surface, D, of the frame A, the edge of one piece abutting against the adjoining piece, as shown in Figs. III and IV. The lever 1 is then moved in the direction of arrow 50, whereby the action of the cam-shaped groove 40 upon roller 39 causes the lever B to move downward and to

bring its head C upon the pieces of pasteboard, at the same time moving the segments 4 and 5. During the motion of these segments 4 and 5 55 the groove 7 in the segment 4 cuts upon roller 8, attached to a slide, 9, guided in head C, moving the same upward. This slide 9 moves, through rod 10, the lever 11, whereby the pawl 12 acts upon the ratchet-wheel 13 and 60 turns the same. This ratchet-wheel 13 is attached to one of a pair of rollers, 14, between which the wire 15, from which the clasps are made, is held, and by their motion move the wire through the channel 16 into a channel, 65 16^x, in the block 17, attached at the lower end of head C and between the shaping-block 25.

In Fig. XI the position of the wire 15 in the block 17 at the beginning of this operation is represented, and Fig. XII shows the position 70 of wire 15 in the block 17 at the end of this operation. After the completion of this operation the cam-groove 18 in segment 5 acts upon the roller 19, attached to the slide 20, guided in the head C, Figs. I, VI, and IX. 75 To this slide 20 the rods 21 21 are attached, these rods being connected to cranks 22 22, fast on the ends of spindles 23, turning in the block 17. The ends of these spindles 23 23 have triangular projections d. By the turning of these spindles one of the projections d will, in connection with a knife-block, e, placed in the block 17, cut the wire 15, after which these projections d d, coming in contact with the ends of the cut-off piece of wire, will bend 85 these ends over the shaping-block 25, situated in the block 17, Figs. XI, XII, and XIII. The ends of the piece of wire (which is to form the clasp) are bent so as to form with the central part angles of about sixty degrees. By changing the dimensions of the cranks 22, or the amount of motion of the slide 20, any desired angle may be obtained.

Fig. XIII shows the position of the several parts when this operation of bending the clasp 95 has been completed. When this operation is completed, the action of the cam-groove 18 turns the crank 22 so far back as to allow a free passage of the clasp-fastener 26 between these projections d d. (See Fig. XIV.) The cam-groove 27 in the segment 5 acts now upon the roller 28, attached to a slide, 29, moving said slide downward. At the lower end of the slide 29 the clasp-fastener 26 is attached by

means of a bolt having a round head, 30. At the beginning of this downward motion of the slide 29 this head 30 comes in contact with an inclined surface, 31, of the rod 25, the upper 5 end of which is loosely connected to the head C, in order that it may be bent outward, and the lower end of which forms the shaping-block for the cut-off wire, as before described. By the action of this head 30 against the inclined 10 surface 31 this lever 25 is bent outward sufficient to bring the lower end or shaping-block of said lever clear of the block 17, and thus allow the clasp-fastener 26 to pass freely downward. The bottom of the fastener 26 is cut out 15 to form an angle of ninety degrees. The further motion of the fastener 26 moves the previously-formed clasp upon the edge of the pasteboard pieces, which form parts of the box, and bends the previously straight central 20 part of the clasp over the edge, at the same time forcing the ends through these side pieces. The forcing of the ends of the clasp through the sides forming the box without any extra external guide is only possible when the 25 ends of the clasp are bent at or about an angle of sixty degrees with the central part of the clasp.

Fig. XIV represents the parts after this operation is completed. The ends of the clasp, 30 after having been passed through the sides, project some distance on the inside. (See Fig. XIV.) The operation of bending these projecting ends to lie flat against the inner surface, and at the same time secure the clasp, is 35 performed as follows: Near the end of the motion of the lever 1 a projection, 32, on said lever comes in contact with the end of a rod, 33, situated in the top end, D, of the frame A, moving the same outward. The forward 40 end of this lever 33 is connected with a bell-crank lever, 34, which operates a plate, 35, so as to move the same upward. (See Figs. I, III, IV, and V, where the same is shown on an enlarged scale.) The upper end of this 45 plate 35 forms, likewise, an angle of ninety degrees, and is provided with teeth 41, which force the projecting inner ends of the clasp upward, bending the same close against the inner surface of said side pieces of the box. 50 By forcing the ends of the clasp through the pasteboard burrs or uneven parts 44 will be produced (see Fig. XIV) on the inner sides

of the box. To press these burrs or uneven parts of the box smooth again, part of the inclined surface at 43 is made flat, so that while 55 passing over these rough parts the same will be pressed smooth. A small cavity, 42, is made in these surfaces for the turned-over part of the clasp. When the above-described operations are completed, a spring, 36, attached to 60 the lever 1, moves the same, as well as all parts connected thereto, back again into their original position, and the spring 37, attached to the frame A and to the lever 33, (see Fig. 1,) moves the rod 33 inward again, and consequently the plate 35, in the position as shown in Fig. XIV. At the same time the head 30 has moved above the incline 31 on lever 25, when a spring, 38, forces the lower end or shaping-block of said lever into its original 65 position, ready for the next operation.

I claim as my invention—

1. The combination of lever 1 and segment 4, provided with cam-groove 7, with slide 9, rod 10, lever 11, pawl 12, ratchet-wheel 13, 75 and rollers 14, and the head C, arranged to operate in the manner and for the purpose substantially as described.

2. The combination of lever 1 and segment 5, provided with cam-groove 18, with slide 20, 80 rods 21, cranks 22, and spindles 23, having triangular ends d, and with shaping-block 25, substantially as specified.

3. The combination of lever 1 and segment 5, provided with cam-groove 27, with slide 29, 85 and clasp-fastener 26, substantially as specified.

4. The clasp - fastener 26, in combination with slide 35, provided with top surfaces inclined at an angle of ninety degrees to each other, the teeth 41 at the top, and the smooth 90 surfaces 43 at the bottom of said surfaces, substantially as and for the purpose described.

5. In a paper-box machine, the combination of the segments 4 and 5, provided with cam-grooves 7, 18, and 27, and turning on centers 95 in the head C, rod 2, and lever 1, with slides 9, 20, and 29, substantially as described.

In testimony whereof I have signed my name to this specification in the presence of two subscribing witnesses.

AUGUST BREHMER.
